US00D929951S

(12) **United States Design Patent** (10) **Patent No.:** **US D929,951 S**
Oh et al. (45) **Date of Patent:** **** Sep. 7, 2021**

(54) **COOLING FAN FOR ELECTRONIC DEVICES**

(71) Applicant: **ABKO Co., Ltd.**, Seoul (KR)

(72) Inventors: **Kwang Geun Oh**, Paju-si (KR); **Tae Hwa Lee**, Goyang-si (KR)

(73) Assignee: **ABKO CO., Ltd.**, Seoul (KR)

(**) Term: **15 Years**

(21) Appl. No.: **35/506,564**

(22) Filed: **Aug. 13, 2018**

(80) **Hague Agreement Data**

Int. Filing Date: **Aug. 13, 2018**

Int. Reg. No.: **DM/200556**

Int. Reg. Date: **Aug. 13, 2018**

Int. Reg. Pub. Date: **Apr. 12, 2019**

(30) **Foreign Application Priority Data**

May 21, 2018 (KR) 30-2018-0023610

(51) LOC (13) Cl. **13-03**

(52) U.S. Cl. ..... **USPC D13/179**

(58) **Field of Classification Search**

USPC D13/179, 182; D23/411, 358, 370, 379, D23/385, 412

CPC H01R 13/6335; H01L 23/3672; H01L 23/4093; H01L 23/467

See application file for complete search history.

(57) **CLAIM**

The ornamental design for a cooling fan for electronic devices, as shown and described.

DESCRIPTION

1.1 is a perspective view;

1.2 is a front view;

1.3 is a rear view;

1.4 is a side view;

1.5 is a side view;

1.6 is a top plan; and

1.7 is a bottom plan view.

In the reproductions, the dash-dash broken lines are for the purpose of illustrating portions of the cooling fan for electronic devices and form no part of the claimed design.

1 Claim, 7 Drawing Sheets
